UNITED STATES PATENT OFFICE.

SAMUEL R. PARRY, OF ROCHESTER, NEW YORK.

LINING-MACHINE.

1,242,720.

Specification of Letters Patent.

Patented Oct. 9, 1917.

Original application filed June 29, 1912, Serial No. 706,706. Divided and this application filed December 29, 1916. Serial No. 139,674.

To all whom it may concern:

Be it known that I, SAMUEL R. PARRY, a citizen of the United States, residing at 222 Mill street, Rochester, in the county of Monroe and State of New York, have invented 5 certain new and useful Improvements in Lining-Machines, of which the following is a specification.

The object of this invention is to produce 10 a machine for lining or covering cardboard, strawboard, chipboard, etc. such as is ordinarily used for making paper boxes, picture mounts, calendar mounts, etc., and more especially to provide a mechanism in 15 this machine with which the continuous web of lining or covering paper is cut at the end of each sheet of cardboard.

This and other objects of this invention will be fully illustrated in the drawing, described 20 in the specification and pointed out in the claims at the end thereof.

In the accompanying drawings,

Figure 1 is a top plan view of the machine.

25 Fig. 2 is a side elevation of the machine viewed from the right hand side of the machine.

Fig. 3 is a sectional elevation on the line 3x—3x of Fig. 1 showing the mechanism 30 by which the cutting mechanism is operated.

Fig. 4 is a detail perspective view of the mechanism for cutting the paper covering.

Fig. 5 is a sectional elevation of the cutting rolls on the line 5x—5x of Fig. 4.

Fig. 6 is a section through the tripping device on the line 6x—6x of Fig. 3.

This application is a division of my prior application No. 706,706, filed in the United 40 States Patent Office June 29, 1912.

In the accompanying drawings like reference numerals indicate like parts.

In the accompanying drawings reference numeral 1 indicates the frame of the machine which consists of two uprights shown 45 partly in side elevation in Figs. 1 and 3 and in top plan view in Fig. 2.

At the front of the frame 1 is provided 50 the feed table 2 upon which the cardboard stock is placed that is to be fed to the machine. Adjacent to this feed table 2 are mounted to rotate the feed rollers 3 and 4 each of which rollers consists of a small shaft having at suitable intervals narrow 55 collars placed thereon. The cardboard

stock is fed forward between these narrow collars by the frictional engagement therewith.

The upper roller 3 rests loosely in the bearings by which it is supported so that 60 the weight of this roller rests on the upper surface of the cardboard stock as it passes through between the rollers 3 and 4. As shown in Fig. 1 five collars are placed upon each of the upper and lower rollers, this 65 number or even more being desirable for heavy cardboard.

In working on light cardboard the number of collars on the upper roll 3 may be decreased and the collars may be moved laterally on the shaft so that each of the remaining collars will only partially engage with the collars on the lower roll, in this way decreasing the frictional engagement 70 between the rollers and the cardboard, which engagement in any case is preferably just enough to secure proper feeding of the cardboard.

Mounted on top of the frame of the machine is the square bar 5 having the spring 80 pressing fingers 6, 6 thereon which bear loosely against the cardboard stock as it is fed forward. The bearing for the bar 5 is split at 7 so that the bar 5 may be rotated to any angular position and clamped therein. This is for the purpose of adjusting it to different thicknesses of cardboard.

Next in order are the rollers 8 and 9, the roll 9 being unyieldingly mounted in the frame of the machine and the roll 8 being 90 yieldingly mounted in the bell crank levers 10 and 11, which levers are pivoted to brackets that are integral with the frame of the machine, the lever 10 being shown in Fig. 3 pivoted at 12 on the bracket 13.

95 Each of these brackets is provided with an arm that projects inwardly, in which a set screw 14 is mounted which bears against the bell crank 10 by which the angular adjustment of it is secured. A bracket 15 is 100 also provided rigid with the frame of the machine to which a spring 16 is connected, which spring in turn is connected to the bell crank 10 by which the roller 8 is yieldingly held in engagement with the roller 9. 105 Similar mountings for the roller 10 are provided on both sides of the machine.

The roller 8 is provided with a series of 110 collars preferably four or more in number, all of which are clamped or keyed to the

shaft. The roller 8 is provided with two collars 17 and 18 with a tripping device or feed regulator rigidly mounted between them. A detail of this arrangement is 5 shown in Fig. 6 in which the shaft or roller 8 is shown provided with the sleeve 19 having a flange on one end thereof and having a reduced end with a shoulder at the other end thereof. On the reduced end is clamped 10 the collar 20 which collar is preferably set up close against the shoulder.

The collars 17 and 18 are thus mounted to rotate loosely on the sleeves 19 and are held in place thereon by the flanges at one end of 15 the sleeves and the collars 20 at the other end. The sleeves 19 and collars 20 are, of course, mounted to rotate with the roller 8 and not independent thereof. Between the flanges on the sleeves 19 as shown in Figs. 2 20 and 3 the tripping device 21 is supported. This tripping device consists of a knife blade 22 that is set eccentrically in the flanges of the sleeves 19 and is normally held in the position shown in Fig. 3, in which 25 position it bears against the sheet of cardboard as it is fed through the machine.

On the knife blade 22 are provided shoulders 23 as shown in Figs. 2 and 3. When one sheet of cardboard is passing under the 30 knife blade with the blade resting loosely thereon, the next sheet of cardboard advances, partly overlapping the preceding sheet and is deflected upward by the knife blade so that it comes into contact with the 35 shoulders 23 by which its further forward movement is arrested as shown in Fig. 3.

As soon as the preceding sheet of cardboard has passed the knife blade 22 the knife 40 blade drops down, being urged on thereto by the pressure of the succeeding sheet of cardboard which in turn is urged forward by the rollers 3 and 4.

The knife blade 22 and the roller 8 by which it is carried are rotated by the advancing sheet of cardboard until the knife has passed clear around the circle, the initial 45 part of the rotation being secured by the direct contact between the advancing sheet of cardboard and the knife blade 22 and the 50 remainder of the rotation being secured by the frictional engagement between the collars 17 and 18 and the sheet of cardboard. The roller 8 is out of balance, the flange on the sleeves 19 being cut away at 24 in order 55 to contribute to this result, so that the knife blade 22 will drop quickly and follow the end of the sheet of cardboard around, being impelled thereto by the frictional engagement between the loose collars 17 and 18 and 60 the roller 8 by which the knife blade is carried so that the sheet of cardboard as it advances, being driven by the rollers 3 and 4, causes the roller 8 to rotate and bring the knife blade 22 once more into engagement 65 therewith. The knife blade does not have

any cutting action and is called a knife simply because of its shape which is preferred on account of convenience, the thin edge of it being easily passed between the edges of consecutive sheets.

On the end of the roller 8 is provided a stud 25, which stud as the roller 8 rotates operates on the lever 26 pivoted at 27 on the frame of the machine. The opposite end of this lever is hook-shaped as shown at 28 for 75 a purpose that will now be described.

After leaving the rollers 8 and 9 the cardboard passes between the rollers 29 and 30 which are solid rollers, the bottom roller 30 being positively driven and the upper roller 29 being driven by the contact of the cardboard which is fed between the two rollers.

The paper web 31 which has been previously coated with paste by the mechanism shown in my prior application above referred to, passes over the roller 30 and first comes into contact with the cardboard and adheres thereto between the rollers 29 and 30. Beyond these rollers, the cardboard and the paper pass on together.

Next after these rollers are arranged the rollers 32 and 33 by which the continuous paper web previously pasted to the successive cardboard sheets is cut at the end of each sheet of cardboard. The upper roller 32 comprises a hollow tube having the longitudinal opening 34 therein on the front side of which is the flange 35. The roller 33 is made preferably as a casting, having three longitudinal ribs thereon spaced 120 degrees apart between centers, which ribs are connected at regular short intervals by circular flanges, the details of which are shown in Fig. 4.

Fastened to one of the longitudinal ribs 105 is the cutting knife 36, which cutting knife engages with the longitudinal recess 34 in the roller 32 for the purpose of cutting the paper web at the end of each sheet of cardboard, or for the purpose of separating consecutive sheets of cardboard that are otherwise connected together by the continuous web of paper 31. The operation of these rolls with their cutting knife is timed to occur at the end of each sheet of cardboard. 110 This result is secured as follows:

The rolls 32 and 33 are spaced from the knife blade 22 of the tripping device 21 by a distance which is sufficient to allow the cam 25 to trip the lever 26 and secure the rotation of the rollers 32 and 33 from the position shown in Fig. 3 to the position shown in Fig. 5 during the interval elapsing from the time that the end of the sheet of cardboard passes the tripping device 21 until it reaches the position of the knife 36 in Fig. 5. The stud or cam 25 is adjusted upon the roller 8 so as to have a delayed action on the lever 26, and this in connection with the distance through which the knife 36 must 115 120 125 130

travel from the position shown in Fig. 3 to that shown in Fig. 5 is sufficient to cause the knife to act on the paper at the end of the sheet of cardboard so as to separate the adjacent edges of the cardboard from each other, which edges are separated from each other approximately by the thickness of the knife blade 22 of the tripping device 21.

The roller 33 is driven by the friction clutch 37 the outer member of which is positively driven by the chain 38 from the sprocket 39. The inner member of the clutch 37 is driven by frictional contact with the outer member which is held in contact therewith by means of the expansion spring 40. The hook-shaped end 28 of the lever 26 is normally held down in engagement with the disk 41 by means of the tension spring 42. The disk 41 has a shoulder 43 thereon by which the hook-shaped end 28 of the lever 26 can engage it to arrest the motion of the roller 33 upon the completion of each revolution thereof, so that the roller 33 will rotate but one for each sheet of cardboard that passes thereover or but once for each time that the tripping device 21 operates through the roller 8 to trip the lever 26. The cutting effect of the rolls 32 and 33 is increased by mounting the roller 32 on bearings that are slightly eccentric thereto, the eccentricity being so located as to crowd the rollers together when they are in the position shown in Fig. 5.

The cutting and feeding rolls of this machine are driven by the gear 44, which gear is mounted to rotate in the frame 1 of the machine. Integral with the gear 44 is the sprocket gear 39, which drives the sprocket chain 38. The sprocket chain 38 drives a sprocket 45 which is integral with the outer members of the clutch 37 through which the cutting roll 33 is driven. The cutting roll 33 is provided with a pinion 46 which meshes with a pinion 47 on the end of the roll 32 by which the rolls 32 and 33 are driven in unison. The gear 44 meshes with the pinion 48, which pinion drives the roll 30.

On the shaft of the roll 30 is mounted the sprocket wheel 49 which drives a sprocket chain 50 which chain engages with the sprocket wheel 51 on the roll 9 and the sprocket wheel 52 loosely mounted on the roll 4, the motion of this sprocket wheel being communicated to the roll 4 through a friction clutch 53, the parts of which are yieldingly held together by the spring 54 which is compressed by the hand wheel 55. This handwheel has a threaded engagement with the end of the roll 4 by which the spring may be compressed and the friction of the clutch regulated at will.

The rollers 3, 8 and 29 are driven solely by frictional contact with the cardboard stock passing through the machine.

A feed table 56 is provided at the front end of the machine on which is provided a gage 57 which is adjustable for the purpose of securing the correct feed of the sheets of cardboard through the machine.

I claim:

1. In a lining machine the combination of a series of pressing rollers arranged in pairs, feeding mechanism adapted to feed sheets of cardboard successively between said pressing rollers, said feeding mechanism operating to prevent the feed of the second sheet until the first sheet has passed a predetermined point, said feeding mechanism operating to separate the beginning of the second sheet from the end of the first sheet as said sheets are fed successively through the machine. 70

2. In a machine for lining paper the combination of a pair of pressing rollers, a pair of cutting rollers arranged on one side of said pair of pressing rollers, a pair of feed regulating rollers arranged on the other side of said pair of pressing rollers, said cutting rollers and one of said feeding rollers being normally idle, said cutting rollers being set in operation by the end of each sheet of cardboard that passes the feeding rollers. 85

3. In a lining machine the combination of a pair of pressing rolls, a pair of cutting rolls on one side of said pressing rolls, a pair of feed regulating rolls on the other side of said pressing rolls, said feed regulating rolls controlling the operation of said cutting rolls, both said cutting and one of said feed regulating rolls normally remaining idle during the passage of a sheet of cardboard by said feed regulating rolls, means on one of said feed regulating rolls 90 to prevent the operation of the feed regulating rolls and the operation of the cutting rolls while a sheet of cardboard is passing the means on said feed regulating roll. 100

4. In a lining machine the combination of a pair of pressing rolls, a pair of feed regulating rolls mounted at the side thereof, a knife blade mounted on one of said feed regulating rolls parallel to the axis thereof, said feed regulating rolls being adapted to 110 permit a sheet of cardboard to pass therebetween, the knife on said feed roll being adapted to bear against said passing sheet of cardboard and prevent the rotation of the roll by which it is carried. 115

5. In a lining machine the combination of a pair of feed regulating rolls, each of said rolls being made up of a shaft with rollers or disks thereon, a knife supported between two disks on one of said rolls, said knife 125 projecting beyond the periphery of said disks and being adapted to bear against the material passed between said rolls, said roll being driven by a light, frictional engagement with the stock passing thereunder, said 130

knife holding the roll against rotation until the end of the passing stock has passed the edge of the knife.

6. In a lining machine the combination of 5 a pair of feed regulating rolls, each of said rolls being made up of a shaft with rollers or disks thereon, a knife supported between two disks on one of said rolls, said knife projecting beyond the periphery of said 10 disks and being adapted to bear against the material passed between said rolls, said knife being adapted to prevent the rotation of said roll during the passage of said material.

7. In a lining machine the combination of 15 a pair of feeding rolls, a knife mounted on one of said rolls and projecting outwardly therefrom, a recess on the other roll adapted to receive said knife to permit the rotation of the first named roll, a sheet of cardboard 20 adapted to pass between said rolls, said knife being adapted to bear on said cardboard and prevent the passage of a second sheet of cardboard.

8. In a lining machine the combination of 25 a pair of feeding rolls, a knife mounted on one of said rolls and projecting outwardly therefrom, a recess on the other roll adapted to receive said knife to permit the rotation of the first named roll, a pair of feeding 30 rolls mounted adjacent to said feed regulating rolls, said rolls being adapted to feed sheets of cardboard yeldingly to said feed regulating rolls, said knife on said feed regulating rolls serving to arrest the second 35 sheet of cardboard until the first sheet of cardboard has passed said knife.

9. In a lining machine, the combination of a pair of feed regulating rolls, one of said rolls having a knife thereon extending along 40 the roll, a pair of feeding rolls placed adjacent to said regulating rolls and adapted to yeldingly feed sheets of cardboard to said regulating rolls, said knife being adapted to bear against the preceding sheet of 45 cardboard and prevent the passage of a succeeding sheet of cardboard, the succeeding sheet of cardboard bearing against said knife and compelling the rotation of said roll after the preceding sheet of cardboard 50 has passed said roll.

10. In a lining machine the combination of a frame, a pair of feed regulating rolls mounted therein, said rolls being adapted to have sheets of cardboard fed therebetween, means on said rolls being adapted to prevent the feeding of a succeeding sheet of cardboard until the preceding sheet of cardboard has passed said rolls.

11. In a lining machine the combination of 60 a frame, a pair of feed regulating rolls mounted therein, said rolls being adapted to have sheets of cardboard fed therebetween, means on said rolls being adapted to prevent the feeding of a succeeding sheet

of cardboard until the preceding sheet of 65 cardboard has passed said rolls, a continuously operating feed roll adapted to feed successive sheets of cardboard to said feed regulating rolls.

12. In a lining machine the combination 70 of a frame, a pair of feed rolls mounted therein, each of said rolls comprising a shaft and collars mounted thereon, the collars on one of said rolls being movable into and out of line with the collars on the other roll. 75

13. In a lining machine the combination of a pair of feed regulating rolls for regulating the passage of sheets of cardboard, one of said rolls being intermittent in its 80 operation and turning a single revolution for each sheet of cardboard passing said roll, means on said roll for arresting the rotation thereof during the passage of the intermediate portion of the sheet of cardboard. 85

14. In a lining machine the combination of a pair of feed regulating rolls for regulating the passage of sheets of cardboard, one of said rolls being intermittent in its 90 operation and turning a single revolution for each sheet of cardboard passing said roll, means on said roll for arresting the rotation thereof during the passage of the intermediate portion of the sheet of cardboard, said means being operated upon by 95 the succeeding sheet of cardboard to complete the operation of said roll.

15. In a lining machine the combination of a pair of feed regulating rolls for regulating the passage of sheets of cardboard, one of said rolls being intermittent in its 100 operation and turning a single revolution for each sheet of cardboard passing said roll, means on said roll for arresting the rotation thereof during the passage of the 105 intermediate portion of the sheet of cardboard, a pair of pressing rolls between which the sheets of cardboard pass from said feed regulating rolls.

16. In a lining machine the combination of a pair of feed regulating rolls for regulating the passage of sheets of cardboard, one of said rolls being intermittent in its 110 operation and turning a single revolution for each sheet of cardboard passing over said roll, means on said roll for arresting the rotation thereof during the passage of the intermediate portion of the sheet of cardboard, said roll continuing its rotation as the end of the sheet of cardboard passes 115 said roll, a cam on said roll, a lever operated by said cam, a cutting device released for operation by the movement of said lever.

17. In a lining machine the combination of a pair of cutting rolls, means for preventing the operation of said cutting rolls and holding them in idle position as the web passes between them, means for releas- 125

- ing said cutting rolls said cutting rolls being adapted to have a paper web passed therebetween to cut the paper web.
18. In a lining machine the combination 5 of a pair of cutting rolls, means for preventing the operation of said cutting rolls and holding them in idle position as the web passes between them, means for releasing said cutting rolls said cutting rolls being 10 adapted to have a paper web passed therebetween to cut the paper web at predetermined points thereon.
19. In a lining machine the combination 15 of a pair of cutting rolls, means for preventing the operation of said cutting rolls and holding them in idle position as the web passes between them, means for releasing said cutting rolls, said cutting rolls being adapted to have a paper web passed 20 therebetween to cut the paper web, sheets of cardboard placed on said paper web, means for coursing the cutting rolls to sever said web at the end of each sheet of cardboard.
20. In a lining machine the combination 25 of a feed regulating roll, said roll having a series of collars thereon, some of said collars being integral with said roll and supporting therebetween a blade parallel to the axis of 30 the roll, others of said collars being mounted to turn on said roll, means for varying the frictional resistance between said collars and said roll.
21. In a lining machine the combination 35 of a feed regulating roll having collars thereon, a knife blade mounted between adjacent collars on one side of said roll and extending parallel to the axis of the roll, said roll being driven by a light, frictional 40 engagement with the stock passing thereunder, said knife bearing with its edge against the passing stock and holding said roll against rotation until the end of the passing stock has passed the edge of the knife.
22. In a lining machine the combination 45 of a feed regulating roll having collars thereon, a knife blade mounted between adjacent collars on one side of said roll and extending parallel to the axis of the roll, 50 said collars being cut away opposite to the knife blade to throw said roll out of balance, said roll being driven by a light, frictional engagement with the stock passing thereunder, said knife bearing with its edge 55 against the passing stock and holding said roll against rotation until the end of the passing stock has passed the edge of the knife.
23. In a lining machine the combination 55 of a frame, bell cranks mounted in said frame, a feed regulating roll mounted in the arms on one side of said bell crank, tension springs connecting between the frame and the other arm of said bell crank, said springs
- tending to yieldingly hold said roll in position.
24. In a lining machine the combination 65 of a frame, bell cranks mounted in said frame, a feed regulating roll mounted in the arms on one side of said bell crank, tension springs connecting between the frame and the other arm of said bell crank, said springs tending to yieldingly hold said roll in position, a set screw on said frame limiting the travel of said roll in one direction.
25. In a lining machine the combination 70 of a frame, levers mounted on said frame, a feed regulating roll mounted in said lever, tension springs connecting between said frame and said levers, said springs tending to yieldingly hold said roll in position.
26. In a lining machine the combination 75 of a frame, levers mounted on said frame, a feed regulating roll mounted in said levers, tension springs connecting between said frame and said levers, said springs tending to yieldingly hold said roll in position, a set screw on said frame limiting the travel of said roll in one direction.
27. In a lining machine the combination 80 of a frame, a pair of cutting rolls mounted to rotate therein, said rolls being geared to rotate together, one of said rolls having a blade thereon, the other of said rolls having a recess therein to receive said blade, means for moving one of said rolls axially 85 toward the other roll as the knife enters said recess.
28. In a lining machine the combination 90 of a frame, a pair of cutting rolls mounted to rotate therein, said rolls being geared to rotate together, one of said rolls having a blade thereon, the other of said rolls having a recess therein to receive said blade, 95 said rolls being adapted to have a web of paper with sheets of cardboard thereon passed therebetween, means for holding said rolls idle while the cardboard is passing between the rolls, said means operating to release said rolls for rotation to cut the 100 web of paper at the end of each sheet of cardboard.
29. In a lining machine the combination 105 of a pair of feeding rolls continuously operating, a pair of feed regulating rolls intermittently operating, said pair of feed regulating rolls being adapted to have sheets of cardboard fed therebetween, a bar mounted between said pairs of rolls and over the path of travel of said sheets, spring 110 fingers on said bar, said bar being angularly adjustable, a table under said bar, said fingers holding said sheets yieldingly down on said table.
30. In a lining machine the combination 115 of a pair of feed regulating rolls, each of said rolls being made up of a shaft with rollers or disks thereon, a knife supported

between two disks on one of said rolls, said knife projecting beyond the periphery of said disks and being adapted to bear against the material passed between said rolls with-
5 out cutting the material.

31. In a lining machine the combination of a roller, a knife edge rigidly mounted therein, means for driving said roller lightly by frictional engagement, said roller being
10 adapted to engage the sheet of passing stock with its knife and have its rotation arrested thereby, said roller resuming its rotation when the sheet of passing stock has passed out of engagement with said knife.

32. In a lining machine the combination 15 of a roller, a knife edge rigidly mounted therein, means for driving said roller lightly by frictional engagement, said roller being adapted to engage the sheet of passing stock with its knife and have its rotation arrested thereby permitting said sheet to pass thereunder without obstruction, said knife operating to deflect and hold a succeeding sheet or sheets, said roller resuming its rotation when the sheet of passing stock has 20 25 passed out of engagement therewith.

In testimony whereof I affix my signature.
SAMUEL R. PARRY.
